SASH AND WINDOW CONSTRUCTION FOR
AUTOMOBILE DOOR BODIESJohn F. Levan, Elkhart, Ind., assignor to Excel
Curtain Company, Elkhart, Ind., a corporation
of DelawareApplication November 14, 1930
Serial No. 495,675

32 Claims. (Cl. 296—48)

This invention has for its object means for holding movable window sashes firmly against rattling in all positions thereof, and particularly relates to means for holding the sashes from rattling, when projected out of a well or recess in which they are housed, when the sashes are open, and where they are unsupported except from within the body at their outer ends when open or partly open. More particularly, the invention has for its object a door and window construction for automobiles where the sash is housed within the door body or an automobile body and is projected through the upper edge thereof and unsupported above the upper edge of the door or above the belt of the automobile body.

Another object of my invention is means for supporting the sash within the hollow body, where the well into which the sash moves is not rectangular because it has to conform to the curve of the fender of the automobile. As is well known, the rear edges of the rear doors of automobiles are cut out at their rear lower corners to conform to the curve of the rear fender. One of the objects of this invention is to provide a supporting and guiding means for a sash movable into and out of the door, the supporting and guiding means conforming to the curve of the edge of the door, due to the rear fender.

The invention consists in the novel features and in the combinations and constructions hereinafter set forth and claimed.

In describing this invention, reference is had to the accompanying drawings, in which like characters designate corresponding parts in all the views.

Figure 1 is a fragmentary inner face view, partly in section, of an automobile door embodying this invention.

Figure 2 is a vertical, sectional view on line 2—2, Figure 1.

Figure 3 is a fragmentary face view of one of the guides or channels for the sash with the tail piece of the sash and contiguous parts being also shown.

Figure 4 is a sectional view on line 4—4, Figure 3.

Figure 5 is a sectional view on line 5—5, Figure 3.

Figure 6 is an enlarged fragmentary view illustrating the tail piece and the guide therefor made to conform to the curve of the fender.

Figure 7 is a sectional view on line 7—7, Figure 6.

Figure 8 is a sectional view on line 8—8, Figure 6.

Figure 9 is a fragmentary elevation of an automobile body embodying this invention.

Figure 10 is an enlarged fragmentary detail view on line 2—2, Figure 1.

This invention comprises, generally, a supporting body, as for instance, the door body of an automobile, guides mounted in the door body, a sash movable into and out of the door body through a slot in the upper edge of the door body, and having members coacting with the guides, each of the guides being in the form of a channel, and pairs of rollers carried by the sash members within the same, and projecting beyond the faces thereof, one roller of each pair running on the inner face of one of the side walls of the channel, and the other roller running along a spring pressed track opposed to the said side wall, and adjacent the other side wall of the channel.

The invention further comprises a member shiftably mounted and usually hinged to the sash and located within the hollow door body or automobile door body and movable relative to the sash in the direction of the plane of the sash during the raising and lowering of the sash from an inclined position to a straight position, when the sash is elevated to conform to the well where the well is not rectangular, as where one lower corner thereof is cut away to conform to the curve of the fender of the automobile body.

I have here illustrated my invention as applied to the front and rear doors of an automobile body and A represents the body, B the fender thereof; C the front door and D the rear door. Each door comprises the usual outer metal sheeting 2 and inner facing or lining 3 and also a top sash plate 4 having a slot 5 therein. This window construction is particularly adapted for convertible or semi-convertible bodies, where the door itself has no frame above the belt and the glass is carried in a sash frame and the sash frame, when the sash is closed, closes against weather stripping or other means around the window opening above the belt.

6 designates the sash of the front door C which is movable into and out of the body A, the sash including a marginal metal frame and glass pane 7.

The sash is also provided with guide members, for convenience called tail pieces 8, located in the door body, and forming downward extensions of the upright members or stiles of the sash. The sash is raised or lowered by well known mechanism including rocker arms 9 having followers movable in a groove in the bottom

5 rail 10 of the sash, these arms being actuated by a crank handle 11, and motion transmitting means, not shown, between it and the arms. The raising and lowering mechanism for the sash forms no part of this invention.

10 12 are sash guide members mounted in the door body, these being in the form of upright channels located near opposite edges of the door body within the body, and being arranged with their open sides toward each other. The tail pieces telescope into the channels, and the tail pieces are provided with means for coacting with the channels to hold the sash tight, not only when the sash is lowered through the slot 5 into the door body, but also when projected various distances out of the door body. As here shown, this means comprises pairs of spaced apart rollers carried by each tail piece near the upper and lower ends thereof, or near the bottom rail of the sash, 15 and at the extreme lower end of the tail pieces, these rollers being carried in recesses in the tail pieces and projecting through passages to the outside of the tail pieces into position to engage opposing walls or parts of the guides 12. As here shown, the tail pieces are in the form of channels and hence, the recesses are the spaces enclosed by the channels. One roller of each pair rolls along the inner face of one of the side walls of the channel 12, and the other roller of each pair is arranged to run along a spring pressed, or resilient track extending along the opposite side of the channel 12, so that the tail pieces and hence, the sash are pressed against one of the walls of the channel and hence, held from rattling.

20 13 designates one roller of each pair, and 14, the other, these rollers being located within the companion tail piece 8 and extending through passages 15 and 16, to the outside of the tail piece where the roller 13 can engage the side wall 17 of the channel shaped guide 12, and the other roller 14 can travel along a spring pressed track 18.

25 45 The rollers are mounted in suitable carriages and also are mounted to avoid wear, and to require very little, if any, lubrication.

50 The carriages here shown include opposed plates 20 and 21 between which the rollers are mounted, floating axles between each of the plates, and each of the rollers, and means pressing on the outer sides of the axles for holding the parts assembled in the channel or recess of the tail piece. The floating axles here shown are balls 22 fitting in sockets located in the center of each roller, and extending into passageways in the plates. The sockets in each roller are connected by a passage 23 for holding the lubricant.

55 60 The means for holding the parts assembled, is here shown as a plate 24 which bears upon the outer sides of the floating axles or balls at 28, and which is clamped in position by a clamping member located between the two rollers.

65 70 The clamping member is here shown as a screw bolt 29 extending through the plate 24 and the plates 20, 21 and threading into the bottom of the recess or channel of the tail piece. This plate 24 has some resiliency. The plate fits between the sides of the recess or guide, or tail piece, and forms a housing for the rollers, and also has angular end flanges 30 which enclose the ends of the plates 20, 21 and also at their edges meet the bottom of the channel of the tail piece. There is sufficient clearance to permit the clamping of the plate 24 tight enough to hold the rollers from looseness, or from binding on the balls.

75 This assembly of the rollers is particularly simple and economical, avoiding the use of fixed axles and consequent looseness, and provides for lubrication for an indefinite period.

80 10 The spring pressed track 18 extends along the adjacent side of the channel 12, is spaced apart therefrom, and is pressed against the rollers to thrust the sash, or tail pieces toward the opposite sides of the channel, by a plurality of springs 32. The springs preferably encircle spaced apart studs 33 extending from the track through the adjacent side walls of the channel 12, and interposed between the track 18 and heads 34 through which the studs slide. The heads 34 are fixed to shrouds or cylindrical casings 35, the shrouds being fixed to the outer side of the channel 12. The track 18 is also formed with an angular flange 36 at its outer edge lapping the edge of the adjacent wall of the channel 12.

85 90 Each of the guides or channels 12 are provided at their lower ends with a buffer or stop 37 on which the tail pieces rest when the sash is lowered to its lowermost position into the door body.

95 100 The pairs of rollers 13, 14 are spaced apart so that the uppermost pairs are located as close as possible to the upper edge of the door, when the sash is in its fully raised position, and the other pairs of rollers are located near the lower ends of the tail pieces. This arrangement particularly holds the sash against rattling, when in fully elevated position as well as when in any intermediate position.

105 110 The relative arrangement of the rollers, tail pieces and the guides, is such that they occupy a minimum space, and are readily located in a limited space in a hollow door body, and as close as possible to the edges of the door body.

115 120 The means for mounting the rollers permits them to be mounted in a limited space, and to work without wearing, and without smearing lubricant with a minimum amount of lubrication which will last indefinitely.

125 130 The rear edge of the rear door D conforms to the curvature of the fender B, and hence the well or opening into which the sash moves is not rectangular, and in order that the sash may be moved completely into the well of the rear door, the guide member or tail piece is movably connected to the sash to shift in the plane of the sash, when the sash is being raised and lowered. It is preferably hinged to the sash and movable along a guide following in a general way the contour of the cut-out of the rear door due to the curvature of the rear fender and means is provided for making the joint rigid between the tail piece and the sash and also for causing the tail piece to follow its guide.

135 140 41 designates the sash of the rear door D, this being of substantially the same construction as the sash 6 and having a tail piece similar to the tail piece 8 in line with the front stile of the sash 41.

145 150 42 designates the pivoted tail piece, this being in the form of a channel and having rollers 43, 44 at its lower end similar to the rollers 13, 14, Figure 1, for coacting with the channel shaped guide 45, which is similar in construction to the guide 12 except that its lower portion is inclined to conform to the curvature of the fender B, it having the spring pressed track 46 similar to the spring pressed track 18. The stile 47 of the sash 41 is provided with a downward extension 48 at its lower end which carries a pair of rollers 49, 51 similar to the rollers 13, 14. The tail piece 42 is hinged or pivoted at 52 to the sash or a rigid

projection 53 depending from the lower edge of the sash, this tail piece being in the form of a channel in cross section and the pivot extending through the opposite walls of the channel and 5 through the projection 53. The sides of the channel adjacent the hinge are prevented from separating by suitable fastening members as rivets 54. The upper end of the tail piece 42 thus embraces the projection 53 and this projection 10 telescopes into the channel of the tail piece 42 and slidably fits the same, thus providing telescoping means on the sash and on the tail piece for relieving the hinge pin of practically all strains except pivotal or torsional strain or relieving the pivot 15 or hinge pin of leverage strains due to the fact that the sash, when closed or out of the well of the door, is supported by the tail pieces within the door. In order to cause the tail piece 42 to follow the guide 45 during the raising and lowering 20 of the sash, sliding interlocking means is provided between the tail piece and its guide 45, this sliding interlocking means being here shown as a pin 56 located near the lower end of the tail piece 42 and projecting beyond one side of the same into a suitable guide provided in the channel or guide 45.

As here shown, the pin hooks under the rear edge of the track 46, the track 46 being made to terminate short of the bottom of the channel 30 shaped guide 45.

In Figure 4, the track 18 meets the bottom of the channel 12 and as seen in Figure 8, the track 46 terminates short of the bottom of the channel 45, thus providing a groove or slot for the pin 56 to 35 slide in.

In order to further hold the door of the sash from rattling, particularly the extreme upper edge thereof, when the sash is lowered into the door body, means, in addition to the pairs of rollers 40 13, 14 are provided, this means being stationary and not movable with the sash or the tail pieces, but being carried by the door body or the guides 12. This means is here shown as spring pressed 45 blocks or buttons 61 having facings 62 of fiber or leather and arranged in openings in the upper ends of the guide channels 12 and 45 and pressed by springs, as flat springs 63 secured at 64 to the outer faces of the side flanges of the channel members 12 and 45 and carrying the block 61 at 50 their free end. Owing to the fact that these blocks are provided with fibrous or leather facings, they do not trace or leave a mark on the stiles of the sash.

Owing to the construction herein described, the 55 sash is noiseless and anti-rattling and there is no felt lining to become loose and scrape off, and also owing to the tail pieces, the guides and the rollers, the sash is firmly supported, when 60 fully open or fully closed or in any intermediate position, and owing to the pivoted tail piece 42, the sash is firmly supported in all the positions thereof when the sash goes into a well shaped to conform to the curve of the fender of the 65 automobile or in other words, the pivoted tail piece 42 provides means for firmly supporting a sash that lowers into a well which conforms to the curvature of a fender.

What I claim is:

1. The combination with a supporting body, of 70 sash guides in the form of channels mounted in the body, a sash having members movable in said guides, a pair of rollers carried by each of said members, one roller coacting with one wall of the channel, and a resilient track extending 75 lengthwise of the channel and opposed to said side

wall of the channel, and along which the other roller travels, the track being formed with studs extending through the adjacent side wall of the channel at spaced apart points, fixed heads through which the studs slide, and springs surrounding the studs and interposed between the heads and said track.

2. The combination with a supporting body, of 80 sash guides in the form of channels mounted in the body, a sash having members movable in said guides, a pair of rollers carried by each of said members, one roller coacting with one wall of the channel, and a resilient track extending lengthwise of the channel and opposed to said side wall of the channel, and along which the other roller travels, the track having an angular flange at the open side of the channel, which flange extends over the edge of the adjacent wall of the channel.

3. The combination of a supporting body having 85 guides therein in the form of channels, a sash having members movable in the channels, said members being formed with recesses having passages opening through the opposite side walls of the recess toward opposite sides of the channels, 90 a carriage mounted in each recess, rollers mounted in the carriage and projecting through the passages beyond opposite sides of said members, and engaging opposing surfaces of each guide.

4. The combination of a supporting body having 95 guides therein in the form of channels, a sash having members movable in the channels, said members being formed with recesses having passages opening through the opposite side walls of the recess toward opposite sides of the channels, 100 a carriage mounted in each recess, rollers mounted in the carriage and projecting through the passages beyond opposite sides of said members, one of said rollers engaging one of the walls of the channel, and a spring pressed track along 105 the other side of the channel on which the other roller rolls.

5. The combination with a supporting body and guides in the form of channels in the body, a sash having members movable in the guides, each of said 110 members being in the form of a channel in cross section and formed with passages through the walls thereof, said passages opening towards opposite walls of the guide, a roller carriage mounted in the channel of each of said 115 members, and rollers carried thereby and extending respectively through said passages for coacting with the guide.

6. The combination with a supporting body and guides in the form of channels, a sash having 120 members movable in the guides, each of said members being formed with a recess and with passages opening towards opposite walls of the channel, a roller carriage mounted in the recess and rollers carried thereby and extending 125 respectively through said passages for coacting with the guide member, said carriage including opposing plates, rollers mounted between said plates, floating axles interposed between the plates and the rollers, a cover plate thrusting 130 against the outer axles, and means for clamping the cover plate in position against the outer 135 axles.

7. The combination with a supporting body and guides in the form of channels, a sash having 140 members movable in the guides, each of said members being formed with a recess and with passages opening towards opposite walls of the channel, a roller carriage mounted in the recess and rollers carried thereby and extending 145 re-

- spectively through said passages for coacting with the guide member, said carriage including opposing plates, rollers mounted between said plates, floating axles interposed between the plates and the rollers, a cover plate thrusting against the outer axles, and means for clamping the cover plate in position against the outer axles, said means coacting with the cover plate between the rollers.
10. 8. The combination with a supporting body and guides in the form of channels, a sash having members movable in the guides, each of said members being formed with a recess and with passages opening towards opposite walls of the channel, a roller carriage mounted in the recess, and rollers carried thereby and extending respectively through said passages for coacting with the guide member, said carriage including opposing plates, rollers mounted between said plates, balls interposed between the plates and the rollers, and constituting floating axles, the plates and the rollers having sockets for the balls.
15. 9. The combination with a supporting body and guides in the form of channels, a sash having members movable in the guides, each of said members being formed with a recess and with passages opening towards opposite walls of the channel, a roller carriage mounted in the recess, and rollers carried thereby and extending respectively through said passages for coacting with the guide member, said carriage including opposing plates, rollers mounted between said plates, balls interposed between the plates and the rollers, and constituting floating axles, the plates and the rollers having sockets for the balls, a cover plate thrusting against the balls, and means for clamping the cover plate in position against the adjacent balls.
20. 10. The combination with a supporting body and guides in the form of channels, a sash having members movable in the guides, each of said members being formed with a recess and with passages opening towards opposite walls of the channel, a roller carriage mounted in the recess, and rollers carried thereby and extending respectively through said passages for coacting with the guide member, said carriage including opposing plates, rollers mounted between said plates, floating axles interposed between the plates and the rollers, a cover plate thrust against the outer axles, and means for clamping the cover plate in position against the outer axles, each of the guides including a spring pressed track located in the channel thereof opposed to the opposite side wall of the channel, one of the rollers coacting with the said spring pressed track.
25. 11. The combination of a hollow body having a slot in the edge wall thereof, a sash movable from the interior of the body through the slot beyond the edge of the body, and having tail pieces, guides mounted in the body for coacting with the tail pieces, pairs of spaced apart rollers carried by the tail pieces and coacting with the guides, and tending to thrust the sash in one direction against the guides, like rollers of the pairs thrusting against like sides of the guides and the guides having spring pressed tracks coacting with the other rollers and thrusting toward the other sides of the guides.
30. 12. The combination of a hollow body having a slot in one edge thereof, a sash having a rigid marginal frame member, the sash being movable through the slot into and out of the body, and means in the hollow body for supporting and guiding the sash comprising a tail piece extend-

ing below the sash member and movably connected to the sash member to shift in the plane of the sash during the raising and lowering of the sash and a guide in the body coacting with the tail piece.

13. The combination of a hollow body having a slot in one edge thereof, a sash having a rigid marginal frame, the sash being movable through the slot into and out of the body, and means in the hollow body for supporting and guiding the sash comprising a tail piece depending below the frame and being pivoted to the sash frame on an axis extending transversely of the plane of the sash during the raising and lowering of the sash and a guide within the body and coacting with the tail piece.

14. The combination of a hollow body having a slot in one edge thereof, a sash having a bottom sash rail, the sash being movable through the slot into and out of the body, and means in the hollow body for supporting and guiding the sash, comprising a tail piece located below the sash rail and pivoted to the sash rail on an axis extending transversely of the plane of the sash during the raising and lowering of the sash and a guide within the door body and coacting with the tail piece, said tail piece being movable on its pivot from an inclined position, when the sash is within the door body into a position parallel to the direction of movement of the sash when the sash is moved out of the door body.

15. The combination of a hollow door body having a slot in one edge thereof, a sash having a marginal frame including stiles movable through the slot into and out of the body, and means in the hollow body for supporting and guiding the sash, comprising a tail piece pivoted to the sash frame on an axis extending transversely of the plane of the sash during the raising and lowering of the sash and a guide within the door body and coacting with the tail piece, said tail piece being movable on its pivot from an inclined position, when the sash is within the door body into a position parallel to the direction of movement of the sash when the sash is moved out of the door body, and said tail piece being in alignment with one of the stiles of the sash when the sash is moved out of the door body.

16. The combination of a hollow door body having a slot in one edge thereof, a sash having a marginal frame member, the sash being movable through the slot into and out of the body, and means in the hollow body for supporting and guiding the sash, comprising a tail piece pivoted to the sash frame member on an axis extending transversely of the plane of the sash during the raising and lowering of the sash, a guide within the door body and coacting with the tail piece, and means for relieving the pivot pin of a leverage action.

17. The combination of a hollow door body having a slot in one edge thereof, a sash having a sash frame, the sash being movable through the slot into and out of the body, and means in the hollow body for supporting and guiding the sash, comprising a tail piece pivoted to the sash frame on an axis extending transversely of the plane of the sash during the raising and lowering of the sash and a guide within the door body and coacting with the tail piece, and means for relieving the pivot pin of a leverage action, said means including rigid telescoping parts on the sash frame and the tail piece adjacent the pivot pin.

18. The combination of a hollow door body having a slot in one edge thereof, a sash having a

- 5 marginal sash frame, the sash being movable through the slot into and out of the body, and means in the hollow body for supporting and guiding the sash, comprising a tail piece pivoted to the sash frame on an axis extending transversely of the plane of the sash during the raising and lowering of the sash, and a guide within the door body and coacting with the tail piece, and means for holding the tail piece from dislodgment from the guide during pivotal movement thereof. 10 19. The combination of a hollow door body having a slot in one edge thereof, a sash including a marginal sash frame, the sash being movable through the slot into and out of the body, and means in the hollow body for supporting and guiding the sash, comprising a tail piece pivoted to the sash on an axis extending transversely of the plane of the sash during the raising and lowering of the sash frame, a guide within the door body and coacting with the tail piece, the tail piece and the guide having sliding interlocking means for holding the tail piece from dislodgment from the guide during the pivotal movement of the tail piece. 15 20. The combination of a hollow door body having a slot in one edge thereof, a sash including a sash frame, the sash being movable in the body through the slot into and out of the body and having tail pieces at its opposite edges, guide means within the body and coacting respectively with the tail pieces, one of the tail pieces being hinged to the sash frame and the axis of the hinge pin extending transversely of the plane of the sash, and the guide coacting with the pivoted tail piece causing the tail piece to be arranged at an inclined angle and to move into a position parallel to the direction of movement of the sash when the sash is moved out of the door body. 20 21. The combination of a hollow door body having a slot in one edge thereof, a sash including a sash frame, the sash being movable in the body through the slot into and out of the body and having tail pieces at its opposite edges, guide means within the body and coacting respectively with the tail pieces, one of the tail pieces being hinged to the sash frame and the axis of the hinge pin extending transversely of the plane of the sash and the guide coacting with the pivoted tail piece causing the tail piece to be arranged at an inclined angle and to move into a position parallel to the direction of movement of the sash when the sash is moved out of the door body, and means forming a rigid joint between the tail piece and the sash frame and relieving the hinge pin from other than pivotal strains. 25 22. In an automobile body having the usual curved fenders and door body, one edge of which conforms to the curve of the adjacent fender, the door body being hollow and having a slot in its upper edge, a sash having a marginal frame, the sash being movable into and out of the door body through the slot and means within the body for supporting and guiding the sash comprising a tail piece hinged to the sash frame and a guide within the body at the edge thereof conforming to the curve in the fender, the tail piece being normally arranged in inclined position when the sash is lowered and to move the guide into an upright position, when the sash is elevated. 30 23. In an automobile body having the usual curved fenders and door body, one edge of which conforms to the curve of the adjacent fender, the door body being hollow and having a slot in its upper edge, a sash movable into and out of the door body through the slot and means within the body for supporting and guiding the sash comprising a tail piece hinged to the sash frame and a guide within the body at the edge thereof conforming to the curve in the fender, the tail piece being normally arranged in inclined position when the sash is lowered and to move the guide into an upright position when the sash is elevated. 35 24. In an automobile body having the usual curved fenders and door body, one edge of which conforms to the curve of the adjacent fender, the door body being hollow and having a slot in its upper edge, a sash including a sash frame, the sash being movable into and out of the door body through the slot and means within the body for supporting and guiding the sash comprising a tail piece hinged to the sash frame and a guide within the body at the edge thereof conforming to the curve in the fender, the tail piece being normally arranged in inclined position when the sash is lowered and to move the guide into an upright position when the sash is elevated, the tail piece and the sash frame having means adjacent the hinge joint connecting them, for holding the tail piece rigid with the sash and relieving the hinge pin from strains other than pivotal strains. 40 25. In an automobile body having the usual curved fenders and door body, one edge of which conforms to the curve of the adjacent fender, the body being hollow and having a slot in its upper edge, a sash movable into and out of the door body through the slot and means within the body for supporting and guiding the sash comprising a tail piece hinged to the sash and a guide within the body at the edge thereof conforming to the curve in the fender, the tail piece being normally arranged in inclined position when the sash is lowered and to move the guide into an upright position when the sash is elevated, the tail piece and the sash having means adjacent the hinge joint connecting them for holding the tail piece rigid with the sash and relieving the hinge pin from strains other than pivotal strains, and the tail piece and the guide having sliding interlocking means for holding the tail piece from dislodgment from the guide. 45 26. The combination of an automobile body having the usual curved fenders and door opening conforming to the curve of the adjacent fender, a hollow door body fitting the door opening and having a slot in its upper edge, a sash including a sash frame, the sash being movable into and out of the door body through the slot, the sash frame having tail pieces at its front and rear edges, one tail piece being rigid with the sash and in line with one of the stiles thereof, the other tail piece being hinged to the sash and arranged in an inclined position when the sash is lowered and movable into a position in line with the other stile of the sash, guide means within the door body and coacting with the tail pieces, the guide means coacting with the pivoted tail piece extending along the edge of the door conforming to the curve of the fender. 50 27. The combination of an automobile body having the usual curved fenders and door opening conforming to the curve of the adjacent fender, a hollow door body fitting the door opening and having a slot in its upper edge, a sash including a sash frame, the sash being movable into and out of the door body through the slot, 55

- the sash frame having tail pieces at its front and rear edges, one tail piece being rigid with the sash frame and in line with one of the stiles thereof, the other tail piece being hinged to the sash frame and arranged in an inclined position when the sash is lowered and movable into a position in line with the other stile of the sash, guide means within the door body and coacting with the tail pieces, the guide means coacting with the pivoted tail piece extending along the edge of the door conforming to the curve of the fender, and means for forming a rigid joint between the pivoted tail piece and the sash and relieving the hinge pin of strain.
28. The combination of an automobile body having the usual curved fenders and door opening conforming to the curve of the adjacent fender, a hollow door body fitting the door opening and having a slot in its upper edge, a sash movable into and out of the door body through the slot, the sash having tail pieces at its front and rear edges, one tail piece being rigid with the sash and in line with one of the stiles thereof, the other tail piece being hinged to the sash and arranged in an inclined position when the sash is lowered and movable into a position in line with the other stile of the sash, guide means within the door body and coacting with the tail pieces, the guide means coacting with the pivoted tail piece extending along the edge of the door conforming to the curve of the fender, and means for forming a rigid joint between the pivoted tail piece and the sash and relieving the hinge pin of strain, the pivoted tail piece and its guide having interlocking means for holding the pivoted tail piece from dislodgment during raising and lowering of the sash.
29. The combination of a hollow body having a slot in one edge thereof, a sash including a sash frame, the sash being movable through the slot into and out of the door body and means for supporting and guiding the sash comprising a tail piece pivoted to the sash frame on an axis extending transversely of the plane of the sash during the movement of the sash, an inclined guide within the body and coacting with the tail piece,
- the sash frame being formed with a projection and the tail piece with a socket in which the projection slidably fits, the projection and socket being located near the hinge pin.
30. The combination of a hollow body having a slot in one edge thereof, a sash including a sash frame, the sash being movable through the slot into and out of the body and means for supporting and guiding the sash comprising a tail piece pivoted to the sash frame on an axis extending transversely of the plane of the sash during the movement of the sash, an inclined guide within the body and coacting with the tail piece, the sash frame being formed with a projection and the tail piece with a socket in which the projection slidably fits, the projection and socket being located near the hinge pin, and means for causing the tail piece to follow the guide during the movement of the sash.
31. The combination with a supporting body, of sash guides in the form of channels mounted in the body, a sash having members movable in said guides, a plurality of pairs of rollers carried by each of said members and spaced apart lengthwise thereof, one roller of each pair coacting with one wall of the channel, and a track comprising a strip extending lengthwise of the channel and opposed to said side wall of the channel and along which track the other roller of each pair travels, whereby the rollers of each pair coat with one side wall of the channel and with the track at spaced apart points, and springs pressing the track inwardly toward said member.
32. The combination of a hollow body having a slot in the edge wall thereof, a sash movable from the interior of the body through the slot and having tail pieces, guides mounted in the body for coacting with the tail pieces, a pair of rollers carried by each tail piece and coacting with the adjacent guide, and tending to thrust the sash in one direction against the guide, one roller of each pair thrusting against one side of the guide, the guide having a spring pressed track coacting with the other roller of that pair and thrusting against the same.

CERTIFICATE OF CORRECTION.

Patent No. 1,928,064.

September 26, 1933.

JOHN F. LEVAN.

It is hereby certified that error appears in the printed specification of the above numbered patent requiring correction as follows: Page 5, line 19, claim 19, strike out the word "frame" and insert the same after "sash" in line 17; line 107, claim 25, after "the" third occurrence, insert door; and line 136, claim 26, after "sash" insert frame; and that the said Letters Patent should be read with these corrections therein that the same may conform to the record of the case in the Patent Office.

Signed and sealed this 14th day of November, A. D. 1933.

F. M. Hopkins

(Seal)

Acting Commissioner of Patents.
